UNITED STATES PATENT OFFICE.

WILLIAM H. BEERS, OF PORTLAND, OREGON.

PIPE-BENDING MACHINE.

1,319,987.

Specification of Letters Patent.

Patented Oct. 28, 1919.

Application filed September 25, 1918. Serial No. 255,573.

To all whom it may concern:

Be it known that I, WILLIAM H. BEERS, a citizen of the United States, residing at Portland, in the county of Multnomah and State of Oregon, have invented new and useful Improvements in Pipe-Bending Machines, of which the following is a specification.

This invention relates to pipe bending machines and consists in certain improvements in the construction thereof as will be hereinafter fully described and pointed out in the claims.

The invention is illustrated in the accompanying drawings as follows:

Figure 1 is a plan view of the machine.

Fig. 2 is a section on the line 2—2 in Fig. 1.

Fig. 3 is an end view of the clamp.

Fig. 4 is a side elevation of the pipe clamp.

1 marks the table, 2 the legs, 3 the cross piece of the frame supporting the table, 4 a rotatively mounted centrally located sheave having a groove corresponding to the size of pipe to be bent, and 5 a sheave operating in conjunction with the sheave 4 and having a corresponding groove.

A sleeve 6 extends through an opening 7 in the table and is secured in the sheave 4. It is provided with a head 8 holding the sheave in proper position on the table. The sheave 5 is journaled on a pin 9. The pin extends through a slot 10 in the table top, this slot being curved with the axis of the sheave 4 as a center. The pin 9 extends through the slot 10 and has a head 11 formed on its end below the table. Rollers 12 are mounted on an axle 13 and operate between the bottom of the table and a plate 14, the plate 14 being suspended from the table top by means of bolts 15. A lever 16 is provided with a pin 17 near one end which is adapted to drop into the sleeve 6 and thus form a pivotal mounting for the lever. The lever has a squared opening 18 which is arranged on a squared extension 19 on the pin 9. A nut 20 is screwed on to the top of the pin securing the lever firmly on the pin. A handle 21 is provided for the lever 16 and may be of any length desired.

A pipe 22 is secured by a clamp 23. The bottom jaw 24 of the clamp has an extension plate 25 and this is adjustably secured to the table by means of bolts 26 which extend through the plate 25 and a slot 27 in a flange 28 extending downwardly from

the table top. A movable jaw 29 is hinged on the stationary jaw 24 and an eye bolt 30 is secured to one of the bolts 26 and is adapted to be swung up into a slot 31 in the end of the movable jaw 29. A wing nut 32 is arranged on the eye bolt. It will be readily seen that by loosening the nut 32 the eye bolt may be swung out of the slot, thus permitting the opening of the clamp. The pipe is put in place and the movable jaw swung to position and the pipe secured by the clamping action of the eye bolt on the jaw 29.

It is desirable to form a support for the pipe extending near to the bending operation. A shoulder 33 is carried by a base plate 34. The base plate is secured on the top of the table by means of bolts 35 which extend through the slots 36 in the table. A similar plate 37 is arranged opposite the shoulder plate 33 so that the bending may be accomplished in either direction as desired.

When it is desired to insert a pipe the lever 16 is removed. This is accomplished by removing the nut 20 which permits the lever to be lifted off the pin, the pin 17 being merely slipped into the opening in the sleeve 6. The sheave 5 can then be moved away from the sheave 4, the slot 10 being provided with extensions 38 to permit of this radial movement of the pin, there being one of the slots 38 at each end of the slot 10. The lever is then put in place and the lever swung by means of the handle. This carries the sheave 5 around the sheave 4 bending the pipe to the curve of the periphery of the sheave. The rotative sheave at the center prevents any strain longitudinally of the pipe and assists in preventing a rupture of the pipe. The rollers 12 engaging the under surface of the table secure the sheave 5 and also through the lever 16 the sheave 4 in place on the table top so that there can be no moving of the sheaves away from the top or away from each other. The squared end of the pin 9 locks the rollers in proper relation to their path of movement.

After the pipe is bent it may be desirable to remove the sheave 5 from the sheave 4 at the end of the bend and for this reason the extensions 38 are provided at both ends of the slot. Further it may be desirable to reverse the bending action under which circumstances the two extensions are desirable.

It will be noted that the sheave 4 deter-

mines the curve of the pipe and consequently the size of this sheave is of some importance. Different sheaves may be supplied of different sizes. Where the sheave 5 is shifted the shoulder 33 and the clamp are adjusted so as to bring them into alinement with the periphery of the sheave. With any change of sheave 4 there must also be a change of the sheave 5, a larger sheave 5 being used with a smaller sheave 4.

What I claim as new is:—

1. In a pipe bending machine, the combination of a table having a curved slot therein; a grooved former concentric with the slot; a sheave; a bearing pin for the sheave, said pin extending through the slot; a swinging mounting for the bearing pin having a pivot at the axis of the former; a roller secured to the mounting and operating on the underside of the table at the side of the slot; and devices for holding the roller in alinement with its direction of travel.

2. In a pipe bending machine, the combination of a table having a curved slot therein; a grooved former concentric with the slot; a sheave; a bearing pin for the sheave, said pin extending through the slot;

a lever swingingly mounted at the axis of the former and secured to the bearing pin; 30 and a head on the pin comprising a roller adapted to engage the under side of the table for holding the sheave in parallel relation with the table and means for maintaining the roller in alinement with its direction 35 of travel.

3. In a pipe bending machine, the combination of a table having a curved slot 40 therein; a first sheave; a sleeve on which the sheave is rotatively mounted, the axis of the sleeve being at the axis of said slot; a second sheave; a pin on which the second sheave is journaled extending through the slot, said sheave having a squared extension; a lever having a pin extending into the sleeve and an opening through which the squared end of the pin extends; means 45 for securing the lever on the pin; and a head on the pin below the table top forming a guide operating against the under side of 50 the table for holding the second sheave in parallel relation with the table.

In testimony whereof I have hereunto set my hand.

WILLIAM H. BEERS.
